SPOON OR SIMILAR ARTICLE

William L. Lafferty, Providence, R. I., assignor to Reed and Barton, Taunton, Mass., a corporation of Massachusetts

Application April 1, 1949, Serial No. 1,769

Term of patent 14 years

(Cl. D54—12)

To all whom it may concern:

Be it known, that I, William L. Lafferty, a citizen of the United States, residing at Providence, in the county of Providence and the State of Rhode Island, have invented a new, original, and ornamental Design for a Spoon or Similar Article, of which the following is a specification, reference being had to the accompanying drawings, forming a part thereof.

In the drawings:

I claim:

The ornamental design for a spoon or similar article, as shown.

WILLIAM L. LAFFERTY.
